US00D820286S

(12) **United States Design Patent** (10) Patent No.: **US D820,286 S**
(45) Date of Patent: **** Jun. 12, 2018**

(54) **TV RECEIVER WITH GRAPHICAL USER INTERFACE**

(71) Applicant: **LG ELECTRONICS INC.**, Seoul (KR)

(72) Inventors: **Uniyoung Kim**, Seoul (KR); **Goeun Lee**, Seoul (KR); **Ryunghwa Rhee**, Seoul (KR)

(73) Assignee: **LG ELECTRONICS INC.**, Seoul (KR)

(**) Term: **15 Years**

(21) Appl. No.: **29/610,001**

(22) Filed: **Jul. 7, 2017**

Related U.S. Application Data

(62) Division of application No. 29/537,376, filed on Aug. 25, 2015, now abandoned.

(30) **Foreign Application Priority Data**

Feb. 25, 2015 (KR) 30-2015-0009563

(51) **LOC (11) Cl.** **14-04**

(52) **U.S. Cl.**

USPC **D14/485**

(58) **Field of Classification Search**

USPC D14/485-495
CPC G06F 3/048; G06F 3/0481; G06F 3/0482; G06F 3/04842; G06F 3/04817

(57) **CLAIM**

The ornamental design for a TV receiver with graphical user interface, as shown and described.

DESCRIPTION

The FIGURE is a front view of a TV receiver with graphical user interface showing our new design. The broken lines showing portions of the TV receiver form no part of the claimed design.

1 Claim, 1 Drawing Sheet
